Primary Examiner — Catherine Ho

(57) **CLAIM**

The ornamental design for a combined lap desk and reading stand, as shown and described.

DESCRIPTION

FIG. 1 is a perspective view of a combined lap desk and reading stand, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof shown in an open position.

The broken lines depict stitching lines and form part of the claimed design.

1 Claim, 8 Drawing Sheets
